UNITED STATES PATENT OFFICE.

RENÉ GRANDJEAN, OF COURBEVOIE, FRANCE, ASSIGNOR, BY MESNE ASSIGNMENTS,
TO RAINBOW LIGHT, INC., OF NEW YORK, N. Y., A CORPORATION OF NEW YORK.

LUMINOUS TUBE.

Application filed August 1, 1925. Serial No. 47,642.

Present invention relates to the luminous tubes used nowadays for advertising and chiefly to those wherein a high vacuum is kept up and wherein the gaseous fluid 5 through which the electric current passes and which is thus illuminated is evolved by suitable salts.

The object of invention is to produce a novel lighting effect by using a fluorescent 10 substance such as zinc sulfide in connection with these tubes. The rear part of the tube or a surface in proximity thereof can for instance be covered with said substance and a known device be used for interrupting 15 periodically the electric current and creating an alternation between the primary illumination of the tube and the secondary illumination produced by the fluorescent substance. Besides the novel effect produced by this alternation of two different lights, another advantage arises through the use of that part 20 of the light which is directed towards the rear of the tube which would otherwise be lost and is according to present invention accumulated by the fluorescent substance which gives it up during the extinction of the primary light.

The appended drawings show by way of example two forms of execution of the invention respectively on Fig. 1 and Fig. 2.

On Fig. 1 which shows a cross section of

the tube, 1 is the support of the tube, 2 the rear part of said tube covered with the fluorescent substance, 3 the front part which is not modified and 4 the supporting panel. 33

Fig. 2 is a diagrammatical side view of a tube according to the second form of execution of the invention with its connections. 2 is a surface covered with the fluorescent substance disposed at the rear and close to 40 the tube, 5 is the mechanism controlling the periodical interruption of the electric current, 3 the luminous tube, 10 the electrode from which the illuminated conducting gaseous fluid evolves, 9 and 9' the dry electrodes, 45 6 the self induction coil used for regulation purposes, 7 the transformer, 8 and 8' the current terminals.

What I claim is:

The combination with a luminous tube 50 containing a conducting gaseous atmosphere to provide a primary source of illumination and intended for advertising purposes, of a coating of fluorescent substance located at the rear of the tube only to provide a secondary source of illumination, and means for interrupting periodically the electric current so as to permit of alternate illumination from said primary and secondary sources. 55

In testimony whereof I have hereunto af- 60 fixed my signature.

RENÉ GRANDJEAN.
